MAGNETIC TAPE TRANSPORT UNIT

Noland E. Vogt, Menlo Park, Calif., assignor to Ampex
Corporation, Redwood City, Calif., a corporation of
California

Filed Apr. 2, 1964, Ser. No. 79,320

Term of patent 14 years

(Cl. D26—5)

FIG. 1

FIG. 2

FIGURE 1 is a front and left side perspective view of a magnetic tape transport unit, showing my new design; and

FIGURE 2 is a rear and right side perspective view. The dominant features of my design reside in those portions shown in full lines on the drawing.

I claim:

The ornamental design for a magnetic tape transport unit, substantially as shown and described.
